UNITED STATES PATENT OFFICE.

LOUIS PERCIVAL HUTTON, OF ORLANDO, FLORIDA.

CHIMNEY-CAP.

1,271,166.

Specification of Letters Patent.

Patented July 2, 1918.

Application filed January 2, 1917. Serial No. 140,114.

To all whom it may concern:

Be it known that I, LOUIS PERCIVAL HUTTON, a citizen of the United States, residing at Orlando, Orange county, in the 5 State of Florida, have invented certain new and useful Improvements in Chimney-Caps, of which the following is a full, clear, and exact specification.

My invention relates to improvements in 10 flues or chimneys, and the same has for its object more particularly to provide a flue or chimney with a protecting hood or cap which is so constructed and arranged that it will permit of the free outflow of fluids 15 or gases therefrom, and at the same time prevent the entrance of air, rain or snow from without into the chimney or flue.

Further said invention has for its object 20 to provide a chimney or flue with protecting means which are so arranged and constructed that the same will be automatically caused to protect the side from which the wind is blowing, and in so doing expose the opposite side of the chimney or flue so as to permit 25 of the free egress of the gases from the flue.

Further said invention has for its object 30 to provide a chimney or flue with a movable protecting hood or cap which is so mounted upon the upper end of the chimney or flue, that the same will be depressed upon the side 35 from which the wind is blowing, and its opposite side be raised to permit of the free egress of gases from the chimney or flue.

Further said invention has for its object 40 35 to provide a chimney or flue with a protecting hood or cap which will automatically adjust itself to close that side of the chimney or flue against which the wind is blowing, and which will automatically right itself to assume a normally horizontal position when the wind ceases.

To the attainment of the aforesaid objects and ends my invention consists in the 45 novel details of construction, and in the combination, connection and arrangement of parts hereinafter more fully described, and then pointed out in the claims.

In the accompanying drawings forming 50 part of this specification wherein like numerals of reference indicate like parts—

Figure 1 is a side view showing the upper portion of a chimney or flue and a protecting hood or cap constructed according to, and embodying my said invention;

Fig. 2 is a central vertical section show-

ing the protecting hood or cap tilted by the action of the wind, and

Fig. 3 is an enlarged detail sectional view showing the means for maintaining the protecting hood or cap movably attached to its support.

Referring to said drawings 10 designates a chimney or flue which may be of any desired shape or form and constructed of any material desired. The said chimney or flue 65 is herein shown as formed of metal, and provided at its upper end with a support comprising a cylindrical section or collar 11 centrally arranged above the top of the chimney or flue and secured in position by 70 means of a plurality of inclined rods 12, 12, having their upper ends secured to the underside of said collar 11, and their lower ends secured to the upper end of the chimney or flue 10. 75

13 denotes a protecting hood or cap which is conical in shape, and may be provided along its edge with a depending rim or flange 13^a. Upon the under side of said hood or cap 12 is secured an annular member or dished plate 14 having a central, depending flange or rim 15 adapted to be received by the collar 11 supported above the upper end of the chimney or flue. To aid in maintaining the hood or cap 13 properly in 85 position upon its support, I preferably slightly round the upper portion of said rim or flange 15 at its point of junction with the dished plate 14.

16 denotes a post which is centrally disposed below the collar 11, and supported upon a suitable support, such as a transverse bar 17 having its opposite ends secured to the inclined rods. The upper end of said post 16 extends into said collar 11, 90 and is provided with an eye 18. Upon the underside of the hood or cap 12 is centrally secured an eye 19, and 20 denotes a chain or other suitable connection having one end secured to said eye 19 on the under side of 95 said hood or cap, and its other end connected to the eye 18 on the post 16, whereby to secure said hood or cap 13 against accidental separation from its support.

The operation of the device is as follows: 105 Normally the hood or cap 13 will be supported in a horizontal position with the rim or flange 15 upon its under side located within the collar 11 supported upon the upper end of the chimney or flue 10. As 110

soon as a current of air coming from any direction strikes the upper surface of the hood or cap 13 at one side thereof it will cause said side to be depressed more or less 5 according to the force of the wind, and at the same time will cause the opposite side of said hood or cap 13 to be raised to permit of the free egress of smoke, gas or fluid from the top of the chimney or flue. As the side 10 of the chimney or flue against which the wind is blowing is protected by the depressed side or edge of the hood or cap 13, no wind, rain or snow can enter the chimney or flue, and thereby prevent or interfere with the 15 flow of smoke, gas or fluid through and from said chimney or flue.

As soon as the wind subsides the hood or cap 13 will automatically right itself, and assume its normal horizontal position, and 20 permit of the uninterrupted flow of fluid from all sides of the chimney or flue.

Having thus described my said invention, what I claim and desire to secure by Letters Patent is:—

25 1. The combination with a chimney or flue of a protecting hood, a support having its lower end secured to said flue and having a collar at its upper end, and means arranged upon the under side of said protecting 30 hood and resting upon the upper end of said collar, said means comprising a portion received within said collar, whereby said protecting hood is tiltingly supported upon said support, substantially as specified.

Copies of this patent may be obtained for five cents each, by addressing the "Commissioner of Patents, Washington, D. C."

2. The combination with a chimney or flue 35 of a protecting hood, a support having its lower end secured to said flue and having a collar at its upper end, and a plate secured to the under side of said protecting hood and resting upon the upper end of said collar, said plate being provided with a depending, annular flange received within said collar, whereby said protecting hood is tiltingly supported upon said support, substantially as specified.

40 3. The combination with a chimney or flue of a protecting hood, a support having its lower end secured to said flue and having a collar at its upper end, means arranged upon the under side of said protecting hood 45 and resting upon the upper end of said collar, said means comprising a portion received within said collar, whereby said protecting hood is tiltingly supported upon said support, and means secured to said 50 protecting hood and to said support and extending through said collar to maintain said hood in operative relation with said support, substantially as specified.

Signed at the city of New York, in the 60 county and State of New York, this 12th day of June, one thousand nine hundred and sixteen.

LOUIS PERCIVAL HUTTON.
